SPEAKER CABINET

Ronald J. Crum, 10208 28th Ave. SW.,
Seattle, Wash. 98146

Filed Mar. 5, 1973, Ser. No. 338,150

Term of patent 14 years

Int. Cl. D14—01; D26—05

U.S. Cl. D26—14 G

FIG. 1 is an isometric view taken from above and looking towards the front and one side of a speaker cabinet showing my new design;

FIG. 2 is an elevational view of the speaker cabinet shown in FIG. 1, looking towards one of the four identical sides of the cabinet; and

FIG. 3 is a top plan view of the speaker cabinet shown in FIGS. 1 and 2. A bottom view is not included because such a view would be substantially like FIG. 3.

I claim:

The ornamental design for a speaker cabinet, substantially as shown and described.
